UNITED STATES PATENT OFFICE

2,488,185

TEMPERATURE EQUALIZING SYSTEM FOR ENCLOSED SPACES

Lawrence H. Gillick, Evanston, and Timothy J. Lehane, Chicago, Ill., assignors, by mesne assignments, to Vapor Heating Corporation, a corporation of Delaware

Application August 23, 1947, Serial No. 770,281

4 Claims. (Cl. 236--1)

1

This invention relates to temperature control systems and has for its principal object the provision of an improved system for automatically varying the delivery of temperature altering media to spaced locations within an enclosed space so as to substantially equalize the temperatures at said spaced locations.

Another and more specific object is to provide a simplified mechanism which will function to proportionately distribute a temperature altering media throughout an enclosed space so as to compensate for the unequal effects of sun-shine, wind and other influences on the temperatures at spaced locations within the enclosure whose temperature is being controlled.

The principles of the present invention are illustrated herein in connection with a temperature control system for a railway car. The principal features, however, may be embodied in structures suitable for use in other situations where similar conditions prevail. It should be understood, therefore, that the particular constructions and manner of use herein shown are intended merely as illustrative and not as a limitation.

The invention, as herein illustrated, automatically controls the distribution of tempered air, as conditions may require, to different locations within a railway car, for example opposite sides of the car, so as to compensate for the disproportionate amount of solar heat which may be received at opposite sides of the car and to also compensate for the disproportionate rate of heat loss at opposite sides of the car, due to wind and other weather conditions which exert their influence on one side of the car to a greater extent than on the other.

Inasmuch as the solar and weather influences are shifted from time to time and thereby alter their effects on different sides of the railway car or other form of enclosed space, arrangements are made whereby the control elements automatically respond to the temperature changes at opposite sides of the improved system of the space whose temperature is being controlled.

The invention is illustrated in accompanying drawings wherein:

Fig. 1 is a fragmentary longitudinal section of a railway car showing the combined heating and cooling apparatus installed in the upper portion thereof.

Fig. 2 is a sectional view taken substantially on line 2--2 of Fig. 1.

Fig. 3 is a vertical section taken substantially on line 3--3 of Fig. 1 looking in the direction of the arrows; and

Fig. 4 is a wiring diagram illustrating the improved control mechanism of the present invention.

The invention may be described briefly as in-

2

cluding an air heater 10 positioned in an overhead duct 12 which extends lengthwise of a railway car 13 and an air cooler 11 which, under certain conditions, cooperate with the heater 10 to deliver tempered air, of suitable temperature, into said duct 12. An electrically operated blower 14 draws air from the interior of the car through a grill 15 and forces it through the heating and cooling elements 10 and 11 and into the distributing portions of the air duct. The distributing portions of the air duct preferably includes branches 16 and 17 which extend lengthwise of the car at opposite sides thereof. Both branches merge together at the point where they communicate with the main duct 12 and are provided with outlets at suitable locations lengthwise of the car. The air inlets 18, 19 to both ducts 16 and 17 are controlled by a proportioning valve 20. When the valve 20 is in a centralized position as shown in Fig. 2 of the drawing, both ducts 16 and 17 receive equal amounts of air from the blower 14. When the valve 20 is moved about its pivotal axis toward the distributing duct 16, the amount of air delivered into the duct 16 is reduced and the amount of air delivered into the duct 17 is increased. The valve 20 is operated by means of a reversible electric motor 21 having a speed reducing connection 22. The direction of movement of the operating motor 21 is controlled by thermostats 23 and 24 located at opposite sides of the car.

The valve 20, as previously indicated, is adjusted by means of the reversible motor 21 to proportion the delivery of heated air into the distributing ducts 16 and 17. The operation of the motor in one direction is controlled by the thermostat 23 and an associated relay 25. The reverse operation of the motor is controlled by the thermostat 24 and an associated relay 26. The electrical connections are indicated in the positions which they assume during the heating cycle of the system when the mercury columns of both thermostats 23 and 24 stand below their upper contacts 27 and 28, respectively. Under this condition, let it be assumed that the side of the car in which thermostat 23 is located is receiving more solar heat than the side in which the thermostat 24 is located. Consequently the thermostat 23 will normally function before thermostat 24. In the present illustration, with both thermostats below their temperature settings, both relays 25 and 26 are energized and both motor circuits are open so that the valve 20 remains in a stationary position. It will also be noted that the closed contact 29 of relay 25 establishes a heating circuit through wire 30, cycle resistor 31, to an auxiliary heater 32, for adding approximately 4° of heat to thermostat 23. This circuit leads from the positive line 33, through wire 34, and closed contact 29, wire 30, resistor 31, auxiliary heater

32 and wire 35 to the negative line 36. An equal amount of auxiliary heat is also applied to the thermostat 24. This heating circuit leads from positive line 33, through wire 37, closed contact 38 of relay 25, wires 39 and 40, through cycle resistor 41 and auxiliary heater 42, and thence through wire 43 to the negative line 36. Inasmuch as the thermostat 23 is assumed to be on the warmer side of the car 13, it will close its contact 27 before thermostat 24 closes its contact 28. The closing of said contact 27 of thermostat 23 de-energizes relay 25. The de-energization of relay 25 opens its contact 29 so as to remove the auxiliary heat from auxiliary heater 32 and closes contact 44 of said relay 25 so as to establish a motor energizing circuit in a direction to move the valve 20 in a direction to decrease the supply of heated air to duct 17 and simultaneously increase the volume of heated air to the duct 16. This motor energizing circuit leads from positive line 33, through wire 45, closed contact 46 of relay 26, wire 47, closed contact 44 of relay 25, wire 48, motor field 49, and thence through the motor armature and wire 50 to the negative line 36. This energizing circuit through the motor will be only momentary since the opening of the relay contact 29 removes the heat from auxiliary heater 32 so as to permit the thermostat 23 to cool sufficiently to cause its mercury column to recede from the upper contact 27. The opening of the contact 27 of thermostat 23 therefore results in re-energizing the solenoid 51 to actuate the relay 25 and thereby re-establishes the auxiliary heating circuit through heater 32. The said solenoid 51 is energized by a circuit composed of positive line 33, wire 52 through resistor 53 and wire 54, through solenoid 51 and wire 55 and resistor 56 and wire 57 to the negative line 36. The circuit is made effective and ineffective by the thermostat 23 which is connected in a shunt around the solenoid. If the thermostat 23 functions again before the thermostat 24, the previous operations will be repeated so as to de-energize the relay 25 and thereby re-establish said momentary circuit through the motor 21 to adjust valve 20 in the direction to further reduce the supply of heated air to duct 17 and increase the delivery of air into duct 16. This operation will continue until the temperatures at both sides of the car are substantially equalized. Assuming now that the temperature of the car at the side in which thermostat 24 is located rises sufficiently to cause said thermostat 24 to function, the functioning of this thermostat de-energizes the solenoid 58 for relay 26 so as to permit its contact 46 to open and also causes its contact 59 to close and thereby establish a reverse circuit through the motor 21. This reverse circuit leads from positive line 33, through wire 34, closed contact 29 of relay 26, wire 60, closed contact 59 of relay 26, wire 61, field 62 of the motor 21, and thence through the motor armature and wire 50 to the negative line 36. The energization of relay 26, while the relay 25 is energized, does not disturb the heating circuit to the auxiliary heater 42. Consequently the mercury column of thermostat 24 will remain above its upper contact until the thermostat 23 is caused to function. However, the functioning of the thermostat 23 is brought about by the effect of its auxiliary heater 32 very promptly and thereby de-energizes the relay 25 to open the auxiliary heater circuit through heater 32 and also opens the contact 46 of relay 26 so as to break the circuit to auxiliary heater 42 to thermostat 24. The valve 20 will remain in

its stationary position while the contacts of both thermostats 23 and 24 are closed. However, if the temperature at either side of the car falls below the temperature of the other side such decline in temperature will result in opening the contacts of the thermostat 23 or 24 at that side of the car and thereby closes an energizing circuit through the motor in a direction to supply additional heated air to the distributing duct at that side of the car. This character of operation brings the temperatures at both sides of the car into balance.

When the thermostat 23 functions to de-energize relay 25 there is a possibility that thermostat 24 will be caused to function before the thermostat 23 cools sufficiently to open its contact 27. Under such conditions the circuit through field 49 of the motor will be broken by the opening of contact 46 of relay 26 and the valve 20 will remain stationary until one or the other of the thermostats 23 or 24 breaks contact. If thermostat 23 is first to open its contact 27 the contact 29 of relay 25 will be closed to complete a circuit through the previously closed contact 59 of relay 26 to energize field 62 of motor 21. If the thermostat 24, under the same conditions, should open its contact 28 before the thermostat 23 opens its said contact 27, relay 26 is energized and a circuit is completed through contact 46 of relay 26 and previously closed contact 44 of relay 25 to energize the motor field 49 and thereby impart movement to motor 21 in a direction to adjust valve 20 in the reverse direction.

It will also be observed that such opposed condition of the relays are present only momentarily, since heat is applied to both thermostats through the energized relay 25 when both thermostats are open at their contacts and that heat is removed from both thermostats when they are both closed. It will be also observed that thermostat 23 is cycled by the opening and closing of relay contact 29 and that thermostat 24 is cycled by opening and closing of relay contact 46. This operation is made possible by the connecting wire 63 which leads from the junction 64 in wire 40 to wire 47.

We claim:

1. A temperature control system comprising, in combination, a temperature altering apparatus for delivering a temperature altering media from a common source to spaced locations within an enclosure, electrically actuated mechanism for proportionately distributing the total of said media to the spaced locations including a valve and a reversible motor for operating the valve in opposite directions, means defining an energizing circuit for operating the motor in one direction, means defining an energizing circuit for operating the motor in the reverse direction, a pair of relays, one of which is provided with an energized closed contact in the first mentioned energizing circuit and a deenergized closed contact in the second mentioned energizing circuit and the other relay is provided with a de-energized closed contact in the first mentioned circuit and an energized closed contact in the second mentioned circuit, whereby either energizing circuit is closed only when one relay is energized and the other relay is de-energized, means defining an energizing circuit for each relay and means for controlling the energization of said relays including thermostats responsive to the temperatures of said spaced locations and set to function at predetermined temperatures, whereby the distribution of said temperature altering media

can be altered only when the thermostat for one spaced location is satisfied and a thermostat for another location remains unsatisfied.

2. A temperature control system comprising, in combination, a temperature altering apparatus for delivering a temperature altering media from a common source to spaced locations within an enclosure, electrically actuated mechanism for proportionately distributing the total of said media to the spaced locations including a valve and a reversible motor for operating the valve in opposite directions, means defining an energizing circuit for operating the motor in one direction, means defining an energizing circuit for operating the motor in the reverse direction, a pair of relays, one of which is provided with an energized closed contact in the first mentioned energizing circuit and a de-energized closed contact in the second mentioned energizing circuit and the other relay is provided with a de-energized closed contact in the first mentioned circuit and an energized closed contact in the second mentioned circuit, whereby either energizing circuit is closed only when one relay is energized and the other relay is de-energized, means defining an energizing circuit for each relay and means for controlling the energization of said relays including thermostats responsive to the temperatures of said spaced locations and set to function at predetermined temperatures, whereby the distribution of said temperature altering media can be altered only when the thermostat for one spaced location is satisfied and a thermostat for another location remains unsatisfied, auxiliary electric heaters for said thermostats, and energizing circuits for the auxiliary heaters connected through the relays associated with the responsive thermostats, whereby the heaters are energized when the thermostats are in corresponding open position and are de-energized when the said thermostats are in corresponding closed positions.

3. A temperature control system for controlling the temperatures at opposite sides of an enclosure, comprising a temperature altering apparatus including a main conduit leading from a supply source of temperature altering media, branch conduits communicating with one end of said main conduit and extending along the opposite sides of the enclosure and adapted to deliver said media into the enclosure serviced by said branch conduits, electrically actuated mechanism including a valve interposed between the inlet ends of said branch conduits and a reversible motor for operating the valve in opposite directions to increase and decrease the delivery of said media to said branches, means defining an energizing circuit for operating the motor in one direction, means defining an energizing circuit for operating the motor in the reverse direction, a pair of relays, one for each side of said enclosure, one relay being provided with an energized closed contact in the first mentioned energizing circuit and a de-energized closed contact in the second mentioned energizing circuit and the other relay being provided with a de-energized closed contact in the first mentioned circuit and an energized closed contact in the second mentioned circuit, whereby either energizing circuit is closed only when one relay is energized and the other relay is de-energized, means defining an ener-

gizing circuit for each relay, and means for controlling the energization of said relays including thermostats responsive to the temperatures of said space locations and set to function at predetermined temperatures, whereby the distribution of said temperature altering media to opposite sides of said enclosure is altered only when the thermostat for one side of said enclosure is satisfied and the thermostat for the other side of said enclosure remains unsatisfied.

4. A temperature control system for controlling the temperatures at opposite sides of an enclosure, comprising a temperature altering apparatus including a main conduit leading from a supply source of temperature altering media, branch conduits communicating with one end of said main conduit and extending along the opposite sides of the enclosure and adapted to deliver said media into the enclosure serviced by said branch conduits, electrically actuated mechanism including a valve interposed between the inlet ends of said branch conduits and a reversible motor for operating the valve in opposite directions to increase and decrease the delivery of said media to said branches, means defining an energizing circuit for operating the motor in one direction, means defining an energizing circuit for operating the motor in the reverse direction, a pair of relays, one for each side of said enclosure, one relay being provided with an energized closed contact in the first mentioned energizing circuit and a de-energized closed contact in the second mentioned energizing circuit and the other relay being provided with a de-energized closed contact in the first mentioned circuit and an energized closed contact in the second mentioned circuit, whereby either energizing circuit is closed only when one relay is energized and the other relay is de-energized, means defining an energizing circuit for each relay, means for controlling the energization of said relays including thermostats responsive to the temperatures of said space locations and set to function at predetermined temperatures, whereby the distribution of said temperature altering media to opposite sides of said enclosure is altered only when the thermostat for one side of said enclosure is satisfied and the thermostat for the other side of said enclosure remains unsatisfied, auxiliary electric heaters for said thermostats, and energizing circuits for said heaters connected through the relays associated with the responsive thermostats, whereby the heaters are energized when the thermostats are in corresponding open position and are de-energized when the said thermostats are in corresponding closed positions.
